UNITED STATES PATENT OFFICE.

ARCHIBALD L. CHUBB, OF GRAND RAPIDS, MICHIGAN.

PLOW.

SPECIFICATION forming part of Letters Patent No. 225,341, dated March 9, 1880.

Application filed July 10, 1879.

To all whom it may concern:

Be it known that I, ARCHIBALD L. CHUBB, of Grand Rapids, in the county of Kent and State of Michigan, have invented an Improvement in Plows, of which the following is a specification.

The nature of this invention relates to certain new and useful improvements in the construction of plows; and the invention consists, first, in the peculiar manner of supporting the colter; and, second, in the peculiar means for adjusting the handles both horizontally and vertically, the pivot-bar of the handles acting as a spreader, extending from the land-side to the mold-board, as fully hereinafter explained.

In the drawings; Figure 1 is a side elevation. Fig. 2 is a rear elevation, partially in perspective. Fig. 3 is a detached view, showing devices for adjusting and securing the lower ends of the handles. Fig. 4 is a sectional perspective, showing the point and section of the mold-board and cutter-standard with cutter removed.

In the accompanying drawings, which form a part of this specification, A represents the iron beam of a plow. That portion, a, forming the standard is curved toward the front, as is usual. The beam is then projected to the front in a horizontal line on its lower edge, to a point in advance of the cutter, and then abruptly curves downward, and terminates at the end in the usual form, and, by being so constructed, greater depth of room is provided between the beam and the operating fore parts of the plow, so that the tendency to clog or choke between the cutter (or jointer, where one is used) and the beam is materially lessened.

To secure the colter B in place a standard, C, the outer face of which is flush with the land-side D, is let into the groove b near the junction of the mold-board with the point, where it is secured by means of the screw or bolt c, which is so inserted as to have a downwardly-oblique draft. To the upper curved end of this standard the colter B is rigidly secured, with its lower end or point resting in the chilled groove in the plow-point. The point and standard, being secured together, are put in place, and the bolt c is drawn tightly, its downwardly-oblique direction forcing the lower end of the cutter B into the chilled

groove d, and holding it there rigidly in place. This groove should be chilled to prevent abrasion caused by sand or dust working into the same when the plow is in operation. This chilling may be done by employing a piece of steel or iron of suitable shape in the sand mold, as a core-print is usually employed.

E represents a spreader-bar provided with screw-threads, and is of proper length, when in place and adjusted, to prevent the land-side and mold-board from being compressed toward each other at or near their rear ends. This bar passes through the land-side D and handles F, and is inserted into the stud e in the inner face of the mold-board G. Nuts f, on either side of the handles, and outside of the land-side, secure this bar in position, and form a fulcrum and fastening for the handles, upon which, by means of the nuts f, they may be laterally adjusted, and upon which they turn when a readjustment of their pitch is required, as hereinafter described.

H is a bracket which is secured to or cast with the standard or land-side, as preferred, and is provided with a slot, g, through which and the lower ends of the handles the bolt h passes, by means of which the handles are secured to said bracket and the pitch of the handles is regulated.

The standard carrying the plow-wheel can be attached to either side of the beam, thus admitting of balancing the plow more perfectly than can otherwise be done.

What I claim as my invention is—

1. In a plow, the colter-standard C, let into a groove in the land-side and secured therein flush with the land-side, in combination with the colter B, secured to such standard at its upper end, and resting at its lower end in a groove, d, formed in the plow-point, substantially as described and shown.

2. In a plow, the combination, with the land-side and mold-board and the handles F, of the spreader-bar E, bracing the land-side and mold-board apart and passing through the handles which are pivoted thereon, and the bracket H, having slot g and bolt h, for adjusting the handles vertically, substantially as described and shown.

ARCHIBALD L. CHUBB.
